INERTIA OPERATED CHOKE FOR SHOTGUNS

Louis M. Denaux, Charleston, S. C.

Application May 21, 1957, Serial No. 660,567

9 Claims. (Cl. 42—79)

This invention relates in general to new and useful improvements in shotgun attachments and more specifically to an inertia operated choke.

In recent years there have been developed many types of automatic chokes for shotguns, the chokes operating on various principles, primarily on the gas operated principle. These prior choke attachments universally have the disadvantage of being complicated and therefore relatively expensive.

It is therefore the primary object of this invention to provide an improved choke attachment for shotguns which after the firing of the shotgun will automatically change the choke thereof, the choke attachment being relatively simple and being formed of readily obtainable materials so that the manufacture and sale thereof is economically feasible.

Another object of this invention is to provide an improved choke attachment for shotguns, the choke attachment being of the inertia operated type and requiring no specially machined parts such as those required in a gas operated type of choke.

Another object of this invention is to provide an improved choke for shotguns, the choke being of an extremely simple construction and includes the normal barrel having the forward end thereof in the form of a plurality of resilient fingers, a sleeve threadedly engaged in the forward end of the barrel and including a frustoconical portion engaging the fingers to effect the changing of choke of the barrel, and an inertia operated operator for selectively rotating the sleeve to vary the choke of the barrel.

A still further object of this invention is to provide an improved inertia operated choke for shotguns, the choke utilizing a choke control sleeve which is threadedly engaged in the forward end of the barrel for selectively engaging finger portions of the barrel to vary the choke thereof, there being provided an operator for selectively rotating the choke control sleeve in response to firing of the shotgun, the operator including a drive finger which is so mounted whereby it may be selectively positioned for driving the choke control sleeve in opposite directions or for rendering the finger inoperative, whereby the choke of the barrel remains constant.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the forward end of a shotgun barrel and shows mounted thereon a first form of choke attachment in accordance with the present invention;

Figure 2 is an enlarged, fragmentary longitudinal sectional view of the forward part of the shotgun barrel of Figure 1 and shows further the details of the choke attachment;

2

Figure 3 is an enlarged fragmentary plan view of the forward end of the shotgun barrel of Figure 1 and shows the choke attachment prior to the firing of the shotgun, a portion of the housing of the choke attachment being broken away and shown in section in order to clearly illustrate the details of the operator thereof;

Figure 4 is an enlarged fragmentary plan view of the forward end of the shotgun barrel of Figure 1 and shows the operator in a choke driving position;

10 Figure 5 is an enlarged transverse vertical sectional view taken substantially upon the plane indicated by the section line 5—5 of Figure 3 and shows the mounting of a gravity actuated weight which is a part of the operator;

15 Figure 6 is an enlarged transverse sectional view taken substantially upon the plane indicated by the section line 6—6 of Figure 2 and shows the specific connection between the drive finger and the inertia actuated operator which permits the varying of the drive of the choke control sleeve;

20 Figure 7 is an enlarged transverse vertical sectional view taken substantially upon the plane indicated by the section line 7—7 of Figure 3 and shows the specific details of the choke control sleeve and the ears carried thereby for engagement by the drive finger;

25 Figure 8 is an enlarged fragmentary plan view of the forward end of the barrel with a portion of the operator of the choke attachment being broken away and shown in section, the operator being shown in an intermediate position;

30 Figure 9 is an enlarged fragmentary side elevational view of a modified form of shotgun barrel and choke attachment, a portion of the barrel and the choke attachment being broken away and shown in section in order to illustrate the details thereof;

35 Figure 10 is an enlarged transverse sectional view taken substantially upon the plane indicated by the section line 10—10 of Figure 9 and shows the details of the inertia actuated weight of the operator; and

40 Figure 11 is an enlarged fragmentary transverse sectional view taken substantially upon the plane indicated by the section line 11—11 of Figure 9 and shows the manner in which the drive finger is rotatably carried by the inertia actuated operator for selective positioning thereof.

45 Referring now to the drawings in detail, it will be seen that there is illustrated in Figures 1 through 8, inclusive, a shotgun barrel 10 which is especially adapted for the reception of a choke attachment. The shotgun barrel 10 is provided at the forward end thereof with a plurality of resilient fingers 12. The resilient fingers 12 are circumferentially spaced and are of a reduced thickness. However, the normal internal diameter defined by the fingers 12 is the same as the internal diameter of the barrel 10. The barrel 10 is provided rearwardly of the fingers 12 with external threads 14 which are relatively coarse. Also, there is mounted on the upper part of the barrel 10 a longitudinally extending sight bar 16 of the conventional type.

50 60 Mounted on the forward part of the barrel 10 is an inertia operated choke which is referred to in general by the reference numeral 18. The choke 18 includes a choke control sleeve 20 which is mounted on the forward end of the shotgun barrel 10 and which includes a forward internal frustoconical portion 22 which is engaged with the fingers 12 so as to urge the fingers 12 inwardly and thereby varying the choke of the barrel 10. The rear part of the choke control sleeve 20 is provided with internal threads 24 which are engaged with the threads 14 to both retain the choke control sleeve on the barrel 10 and also to longitudinally posi-

65 70 75 80 85 90 95

tion the choke control sleeve 20 so as to vary the choke of the barrel 10.

It is to be noted that the rear part of the choke control sleeve 20 includes an outwardly projecting, annular collar 26. The collar 26 is interrupted by circumferentially spaced recesses 28, as is best shown in Figure 7, to form a plurality of circumferentially spaced ears 30.

In order to facilitate the rotation of the choke control sleeve 20 to automatically vary the choke of the barrel 10 after the firing thereof, there is mounted on the barrel 10 a gravity actuated operator or actuator assembly which is referred to in general by the reference numeral 32. The operator assembly 32 includes an elongated inertia actuated operator or actuator 34. The operator 34 includes an elongated rear portion 36 of channel-shaped cross section which functions as a continuation of the sight bar 16. The rear portion 36 is guidingly engaged on a support pin 38 which includes a head 40 and an intermediate recess 42. The rear portion 36 is provided with an opening 44 to clear the head 40 and thus facilitate the removal of the operator 34 from the pin 38.

The operator 34 also includes a forward portion 46 which is square in cross section and which has a longitudinally extending, circular bore 48 therethrough. An elongated, longitudinally extending slot 50 opens the bore 48 through the bottom of the forward portion 46. The upper part of the bore 48 opens into a relatively wide portion 52. Carried by the forward part of the barrel 10 is a second pin 54 having an enlarged head 56 which is slidably received in the opening 52. The pin 54 extends through the slot 50. It is to be understood that the slot 50 and the opening 52 extending through the forward end of the operator 34 may be disengaged from the pin 54.

The operator 34 includes an intermediate vertical wall 58 which forms a divider between the forward portion 46 and the rear portion 36. Mounted within the forward portion 46 is a coil spring 60 which has one end thereof bearing against the wall 58 and the opposite end thereof bearing against the pin 54. Thus the operator 34 is normally urged rearwardly to the position illustrated in Figure 2 by the coil spring 60.

Carried by the forward portion 46 of the operator 34 is a drive finger assembly which is referred to in general by the reference numeral 62. The drive finger assembly 62 includes a circular cross sectional carrier 64 which is positioned in the forward end of the forward portion 46, as is best shown in Figure 3. The carrier 64 is retained within the operator 34 by means of an operating lever 66 which is threadedly engaged in the carrier 64 and which extends transversely therefrom. The lever 66 passes through a circumferential slot 68 in the forward portion 46, as is best shown in Figure 6, and permits the drive finger assembly 62 to be rotated 180 degrees. The purpose of so mounting the carrier 64 will be described in more detail hereinafter.

The forward part of the carrier 64 is provided with a slot 70 in which there is mounted a rear part 72 of a drive finger 74. The drive finger 74 is curved and is of the cam type. The drive finger 74 includes a shoulder 76 which is engageable with the forward end of the carrier 64 to limit pivoting of the drive finger 74 about a pivot pin 78 which is used to pivotally mount the drive finger 74 relative to the carrier 64. A coil spring 80 mounted in the recess 70 and bearing against the rear portion 72 normally urges the drive finger 74 to the position illustrated in Figure 3.

The choke attachment 18 may be removed from the barrel 10 by first unscrewing the choke control sleeve 20. Then, by removing the lever 66, the drive finger assembly 62 may be removed from the operator 34. The operator 34 may then be moved rearwardly until the pin 54 passes out of the forward end of the operator 34 and the pin 38 is aligned with the opening 44. The operator 34 may then be lifted off the pin 44. Incidentally, it is pointed

out that the rear end of the carrier 64 functions as a stop to limit rearward movement of the operator 34 due to the urging of the spring 60.

Assuming it is desired to increase the choke of the barrel 10 during a sequence of firing, the choke control sleeve 20 and the operator assembly 32 are positioned in the manner illustrated in Figure 3. When the gun of which the barrel 10 is a part is fired, the barrel 10 will move rearwardly and the operator assembly 32 will maintain substantially a fixed position due to the inertia which must be overcome to move it. As a result, the collar 26 will move rearwardly and engage the drive finger 74, as is best shown in Figure 4. The choke control sleeve 20 will then be rotated and further threaded onto the barrel 10 so as to move longitudinally rearwardly along the barrel 10. This will increase the choke of the barrel 10 by compressing the spring fingers 12. After the gun has been fired, it will again move forwardly, at which time the spring finger 74 will pivot about the pivot pin 78 and permit the choke control sleeve 20 to move forward without being turned backward from the position it had been originally turned. Upon the next firing of the gun of which the barrel 10 is a part, the drive finger 74 will be engaged by one of the ears 30. The sequence is repeated until such time as the drive finger 74 is positioned in the last one of the slots 28, at which time no further advancing of the choke control sleeve 20 is possible.

If it is desired to open the choke of the barrel 10 during a firing sequence, the choke control sleeve 20 is positioned on the barrel 10 in a position of maximum choke. The drive finger assembly 62 is then rotated 180 degrees from the position illustrated in Figure 3 so that when the choke control sleeve 20 moves rearwardly relative to the drive finger 74, it will be cammed in a direction opposite from that shown by the arrow in Figure 4 on the annular collar 26. Further, if it is desired to render the automatic feature of the choke inoperative, this can be accomplished by moving the lever 66 to an upright position, such as shown in Figure 6. In this position the drive finger 74 faces upwardly and will freely pass into one of the slots 28 so as to not drive the choke control sleeve 20.

Referring now to Figures 9, 10 and 11 in particular, it will be seen that there is illustrated a modified form of shotgun barrel and choke assembly. The shotgun barrel 82 is referred to in general by the reference numeral 82 and with the exception of the fact that it is not provided with a sight bar such as the sight bar 16 it is identical with the barrel 10. The extreme forward end of the barrel 82 is in the form of a plurality of resilient fingers 84 and disposed rearwardly of the finger 84 is an externally threaded portion 86. Threadedly engaged on the forward end of the barrel 82 is a choke control sleeve 88 which is identical to the choke control sleeve 20. The choke control sleeve 88 includes a forward internal frustoconical portion 90 which is engaged with the fingers 84 for varying the choke of the barrel 82. The rear part of the choke control sleeve 88 includes an annular collar 92 which is divided into a plurality of circumferentially spaced ears 94 by means of circumferentially spaced slots 96.

In order to facilitate the rotation of the choke control sleeve 88 to vary the choke of the barrel 82, there is carried by the barrel an operator assembly which is referred to in general by the reference numeral 98. The operator assembly 98 includes an inertia actuated operator 100 which is in the form of a large annular weight. Secured to the underside of the barrel 82 as by welding is an elongated key 102. The operator 100 is provided with a keyway 104 in which the key 102 is received. The operator 100 is thus prevented from rotating.

As is best shown in Figure 9, the key 102 has a rear portion thereof removed as at 105 to form space for a coil spring 106. Further, the operator 100 includes a projecting portion 108 which projects into the removed

part 105. The spring 106 bears against the projecting part 108 of the operator 100 to urge the operator 100 to the left to its normal inoperative position of Figure 9. A stop 110 in the form of a setscrew limits the rearward movement of the operator 100.

The upper part of the operator 100 includes a longitudinal bore 112 which does not extend the full length of the operator 100. Seated in the bore 112 is a carriage 114 which is identical with the carriage 64. The carriage 114 is a part of a drive finger assembly 116 which is identical with the drive finger assembly 62 and need not be described in more detail. The drive finger assembly 116 does include a drive finger 118 which is identical to the drive finger 74, which drive finger 118 is pivotally mounted with respect to the carriage 114 by means of a pivot pin 120.

In order to facilitate the positioning of the drive finger assembly 98 with respect to the operator 100, the operator 100 is provided with a transverse slot 122 in the central portion thereof, which slot opens downwardly into the bore 112. Disposed within the slot 122 and carried by the carriage 114 is a lever 122. The lever 122 is used to rotate the carriage 114 within the bore 112.

Inasmuch as the only difference between the operator assembly 98 and the operator assembly 32 is the details of the construction of the operator, it will be readily apparent that the operation of the shotgun including the barrel 82 will be identical with the operation of the shotgun including the barrel 10, as described above. Accordingly, description of the specific details of the operation of the choke assembly carried by the barrel 82 is not believed to be necessary.

From the foregoing description of the two forms of choke assembly disclosed, it will be readily apparent that there has been devised a very simple automatic choke assembly which may be built at a minimum of cost and which when placed into operation has relatively few moving parts which are subject to wear and breakage. Thus, there has been devised a relatively inexpensive automatic choke which is free from the normal operating troubles experienced with other types of automatic chokes.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve.

2. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread

means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve, said operator being of the inertia actuated type.

3. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve, said operator being of the inertia actuated type, spring means connected to said operator for returning said operator to an inoperative position.

35. 4. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve, a spring loaded pivotal connection between said operator and said drive finger whereby said drive finger may be withdrawn from between adjacent ones of said ears without effecting reverse rotation of said choke control sleeve.

55. 5. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve, a rotatable connection between said drive finger and said operator whereby said

drive finger may be selectively rotated whereby said drive finger may be selectively positioned in forward drive, reverse drive and inoperative positions.

6. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an operator mounted on said barrel for longitudinal movement thereon, a cam type drive finger carried by said operator and engageable with said ears to rotate said choke control sleeve, a rotatable connection between said drive finger and said operator whereby said drive finger may be selectively rotated whereby said drive finger may be selectively positioned in forward drive, reverse drive and inoperative positions, a spring loaded pivotal connection between said operator and said drive finger whereby said drive finger may be withdrawn from between adjacent ones of said ears without effecting reverse rotation of said choke control sleeve.

7. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an inertia actuated operator mounted on said barrel for longitudinal movement thereon, a cam type drive finger carried by said operator and engageable with said ears to rotate said choke control sleeve, a spring loaded pivotal connection between said operator and said drive finger whereby said drive finger may be withdrawn from between adjacent ones of said ears without effecting reverse rotation of said choke control sleeve.

8. A choke assembly for shotguns and the like, said choke assembly comprising a gun barrel having a forward end in the form of a plurality of individual resilient

fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an inertia actuated operator mounted on said barrel for longitudinal movement thereon, a cam type drive finger carried by said operator and engageable with said ears to rotate said choke control sleeve, a rotatable connection between said drive finger and said operator whereby said drive finger may be selectively rotated whereby said drive finger may be selectively positioned in forward drive, reverse drive and inoperative positions.

9. A choke assembly for shotguns and the like, said choke assembly comprising a gun barrel having a forward end in the form of a plurality of individual resilient fingers, a choke control sleeve engaged over said forward end, said choke control sleeve including an interior frusto-conical portion engaging said fingers, thread means on said barrel and said choke control sleeve for positioning said choke control sleeve longitudinally of said barrel to vary the choke of said barrel by varying the engagement of said frusto-conical portion with said fingers, and control means carried by said barrel for rotating said choke control sleeve to vary the longitudinal position of said choke control sleeve, said control means including a plurality of circumferentially spaced ears on said choke control sleeve, an inertia actuated operator mounted on said barrel for longitudinal movement thereon, a cam type drive finger carried by said operator and engageable with said ears to rotate said choke control sleeve, a rotatable connection between said drive finger and said operator whereby said drive finger may be selectively positioned in forward drive, reverse drive and inoperative positions, a spring loaded pivotal connection between said operator and said drive finger whereby said drive finger may be withdrawn from between adjacent ones of said ears without effecting reverse rotation of said choke control sleeve.
